Primary Examiner — L. A. Grabenstetter*(74) Attorney, Agent, or Firm* — Amster, Rothstein & Ebenstein LLP**(57) CLAIM**

We claim the ornamental design for a charger box, as shown and described.

DESCRIPTION

FIG. 1 is a front elevation view of a charger box showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines, and regions bounded on all sides by broken lines, depict features of the charger box that form no part of the claimed design.
